UNITED STATES PATENT OFFICE.

CHARLES G. SERVIS, OF LOGAN, IOWA.

PACKAGE-TIE.

1,385,956.

Specification of Letters Patent. Patented July 26, 1921.

Application filed May 11, 1920. Serial No. 380,561.

To all whom it may concern:

Be it known that I, CHARLES G. SERVIS, a citizen of the United States, residing at Logan, in the county of Harrison and State 5 of Iowa, have invented certain new and useful Improvements in Package-Ties, of which the following is a specification.

This invention relates to package ties and more particularly to device for tying packages of letters and the like for transportation through the mail.

One important object of the invention is to provide an improved device embodying a tying cord which can be quickly and easily 10 passed around a package and detachably held in position against accidental displacement.

Another object of the invention is to provide an improved package tie embodying a 15 protecting plate for engaging the package having a binding cord attached at one end thereto, the cord being adapted to be passed around the package for holding the letters or other pieces forming the package against 20 displacement, the protecting plate having means for engaging the cord so as to prevent 25 accidental movement of the cord in relation thereto and on the package, said protection plate also having an improved means 30 for detachably engaging the free end of the cord so as to prevent accidental displacement thereof.

A further object of the invention is to provide an improved package tie in which 35 the binding cord can be readily and quickly secured in place against accidental movement.

A further object of the invention is to provide an improved tie which can be continuously used, and which is especially designed 40 to take the place of common binding cord now generally used by the Post Office Department for securing packages of letters together.

A still further object of the invention is to provide an improved package tie of the 45 above character which is durable and efficient in use, one that is simple and easy to manufacture, and one which can be placed 50 upon the market at a reasonable cost.

With these and other objects in view, the invention consists in the novel construction, arrangement and formation of parts as will be hereinafter more specifically described, 55 claimed and illustrated in the accompany-

ing drawings, forming a part of this specification, in which drawings:

Figure 1 is a perspective view of the improved package tie, showing the same in use.

Fig. 2 is a longitudinal vertical section 60 through a package tie showing the same in position on a package of letters or the like.

Fig. 3 is a longitudinal vertical section 65 through the package tie showing the improved clamp carried thereby, designed to hold the free end of the binding cord against accidental displacement.

Fig. 4 is a vertical central transverse section 70 through the improved package tie showing the same in use.

Fig. 5 is a plan view of the improved package tie, the central post being shown in section.

Referring to the drawings in detail, wherein similar reference characters designate corresponding parts throughout the several views, the letter A generally indicates the improved package tie; and B, a package of letters which the same is associated with.

The improved package tie A includes a substantially flat rectangular plate 10, which can be formed of any material, preferably of hard rubber or the like. The plate 10 is of such a size as to completely overlie the 85 package to be tied, so that a protecting cover will be provided for the same.

An upstanding post 11 is carried by the central portion of the plate 10 and is connected thereto in any preferred manner. If 90 so desired, the post 11 may be formed integral with the plate and molded therewith when the same is formed. The upper end of the post 11 is provided with a retaining head 12 which is adapted to overlie the plate 10 95 and the post itself is provided with a diametrically extending opening 13 which receives one end of the binding cord 14. The end of the binding cord 14 which is placed through the opening 13 is provided with a 100 knot 15 so as to prevent accidental displacement thereof through said opening. One side edge of the plate is provided at the longitudinal center thereof with a downwardly and outwardly inclined opening 16 which is 105 substantially at an angle of 20° and the binding cord 14 is adapted to be threaded through the opening. The opposite end of the plate at the longitudinal center thereof is provided with an inclined guide groove 17 110

which is adapted to receive the binding cord when the same is placed longitudinally around a package.

- The plate 10 is also provided with a clamp 18 which is designed to detachably hold the free end of the binding cord in position and this clamp as shown includes a block of relatively soft rubber 19 which is embedded in the upper surface of the plate 10 as at 20. 5
- 10 The block 19 is arranged at one side of the longitudinal center of the plate and has its upper surface gradually inclined toward one end thereof. The upper surface of the block 19 is engaged by a flexible retaining 15 plate 21 which is also preferably formed of soft rubber. This retaining plate 21 extends beyond the opposite end of the block 19 and has one end thereof riveted or otherwise secured as at 22 to the plate 10.
- 10 In operation of the improved package tie, 20 the plate 10 is placed on the upper surface of the package of letters or the like to be held together, and the end of the cord 14 which is placed through the opening 13 is 25 passed longitudinally around the package. The same is then placed in the groove 17 and brought over the upper surface of the plate and around the center post 11, after which the same is passed transversely 30 around the package and the free end is inserted between the retaining plate 21 and the block 19. Owing to the fact that the retaining plate 21 and the block 19 are formed of relatively soft rubber, the same 35 will firmly grasp the free end of the cord and frictionally hold the same against accidental displacement.

Thus it can be seen that an improved package tie has been provided which can be readily associated with a package of letters or removed therefrom when so desired. The cord can be used over and over again and thus it can be seen that not only an economical device has been provided but also a time 45 saver.

Changes in details may be made without departing from the spirit or scope of the invention; but,

I claim:

- 50 1. A package tie comprising a flat plate, an upstanding headed post carried by the central portion of the plate, the plate having its opposite ends provided respectively with an inclined guide opening and an inclined 55 guide groove, a binding cord having one end secured to the central post, the cord being arranged in said inclined guide opening and adapted to engage in said groove

when the same is passed around a package, and a releasable resilient clamp carried by 60 the upper surface of the plate at one side of the post for detachably receiving the free end of said binding cord.

2. A package tie comprising a flat plate, a headed post carried by the plate, a binding cord at one end secured to the post and adapted to be passed transversely and longitudinally around a package, the upper surface of the plate at one side of the post having a recessed portion a block of relatively soft rubber secured in said recessed portion, the upper surface of said block being inclined, a retaining plate of relatively soft rubber arranged to overlie said block, and means for securing one end of said retaining plate to said first mentioned plate, the retaining plate and block being adapted to receive the free end of the binding cord therebetween. 70

3. A package binder comprising a plate 80 having guides formed centrally on its opposite ends, a central headed post carried by the upper surface of the plate, the post having an opening formed therein, a binding cord arranged in said opening and having one end thereof knotted to prevent movement through said opening, a soft rubber friction block carried by the plate, and having its upper surface arranged above and at an incline to the plate, and a second soft 85 rubber friction block secured to the upper surface of the plate and arranged to overlie said first mentioned block, the soft rubber block being adapted to frictionally engage 90 the free end of the binding cord. 95

4. A package tie comprising a flat plate, an upstanding headed post carried by the central portion of the plate, a plate having its opposite ends provided respectively with an inclined guide opening and an inclined guide groove arranged in alinement with each other, a binding cord having one end secured to the post, the cord being arranged in said inclined guide opening and adapted to engage in said groove when the same is passed around a package, a soft rubber friction block carried by the plate and arranged at one side of the post and having its upper surface arranged above and at an incline to the plate, and a second resilient 100 friction member secured to the upper surface plate and overlying said block, the soft rubber block and the resilient friction plate being adapted to frictionally engage the free end of the binding cord. 110

CHARLES G. SERVIS.
